The ornamental design for hybrid aeroponic/hydroponic growing system, as shown and described.

DESCRIPTION

FIG. 1 is a top perspective view of a hybrid aeroponic/hydroponic growing system;

FIG. 2 is a bottom perspective view of a hybrid aeroponic/hydroponic growing system;

FIG. 3 is a top view of a hybrid aeroponic/hydroponic growing system;

FIG. 4 is a bottom view of a hybrid aeroponic/hydroponic growing system;

FIG. 5 is a side view of a hybrid aeroponic/hydroponic growing system;

FIG. 6 is an opposing side view of a hybrid aeroponic/hydroponic growing system;

FIG. 7 is an end view of a hybrid aeroponic/hydroponic growing system; and,

FIG. 8 is an opposing end view of a hybrid aeroponic/hydroponic growing system.

The broken lines in the drawings depict portions of the hybrid aeroponic/hydroponic growing system that form no part of the claimed design.
